BY *R. D. Shumate Jr.*
ATTORNEY

UNITED STATES PATENT OFFICE.

WILLIAM A. KIMBELL, OF BIRMINGHAM, ALABAMA.

PLOW.

1,157,399.

Specification of Letters Patent. Patented Oct. 19, 1915.

Original application filed January 23, 1915, Serial No. 3,959. Divided and this application filed June 14, 1915. Serial No. 33,858.

To all whom it may concern:

Be it known that I, WILLIAM A. KIMBELL, a citizen of the United States of America, residing at Birmingham, in the county of Jefferson and State of Alabama, have invented certain new and useful Improvements in Plows, of which the following is a specification.

My invention relates to an improvement in plows having for its object to provide a novel and effective manner of attaching the plow standard to the beam so as to transfer to the beam, rather than to the bolts that connect the standard thereto, the thrusts and strains to which the beam is subjected in service.

In a pending application Serial No. 3959, of which this is a divisional application, I have shown and claimed certain novel means for the mounting of the plow point and, if desired, a sweep upon a standard formed by a bent bar of single thickness so as to reduce to a minimum the obstruction offered by the standard in plowing.

One object of my present invention is to provide means for fastening a standard of single thickness to the beam so that the latter will to a large extent reinforce and securely hold the standard therein and will at the same time permit its adjustment to vary the angular disposition of the plow point relative to the beam for plowing at different depths.

In the accompanying drawings I have illustrated what I regard as the preferred embodiment of the principles upon which my present invention is based, but it is to be understood that I do not intend thereby to limit myself to the exact construction and arrangement of parts shown.

Referring to the drawings: Figure 1 is a side elevation of the plow beam with the standard connected thereto and shown in one of its adjusted positions. Fig. 2 is a similar view broken away to show the standard in full elevation and in a different adjusted position. Fig. 3 is a cross sectional view on the line $\alpha-\alpha$ of Fig. 1.

Similar reference numerals refer to similar parts throughout the drawings.

In the preferred embodiment of my invention which is illustrated in the drawings the plow is shown with a wooden beam 1 having handles 2 of usual construction, the beam having in its underface a narrow, ver-

tical, longitudinally disposed slot 3 extending part way up through the beam from near the handles to a point substantially midway of the beam where the slot extends vertically upward, and, if desired, passes through the top of the beam. The slot is made just wide enough to receive the upper elongated portion 4 of the standard 5 which is formed preferably of a single bent metal bar having at its forward end an upturned curved lug 6 in which I provide a series of bolt holes 7. The upper portion 4 of the standard which fits in the slot 3 is of substantial length and is pivotally connected at its rear end to the beam by a cross bolt 8 disposed near the rear end of the slot 3. The rear vertical edge of the lug 6 and the series of bolt holes 7 therein are both struck on arcs from bolt 8 as a center and the rear wall 9 of the vertical extension of the slot 3 is struck on a similar curve. A bolt 10 is passed through the beam and through one of the bolt holes 6 to attach the forward end of the standard to the beam adjustably so that the plow point 11 may be set at the desired angle. It will be noted that the standard is of single thickness and its foot portion 5 is brought forward on a gradual curve to the point of attachment thereto of the plow point 12. The rear end wall 13 of the slot 3 is curved so that when the standard is set in the position shown in Fig. 2, the rear curved edge of the standard beyond its pivot 8 will have an extended bearing. The holes for the bolts 8 and 10 are designed to leave sufficient play to permit the standard to take its bearing against the beam in the manner which will now be described.

It being my purpose to so connect the standard to the beam that the latter takes practically all of the strain from the fastening bolts, it will be noted that the rear curved face of the extension lug 6 will, in all operation positions, take a firm and solid bearing against the curved wall 9 of the slot, thus relieving the bolts of all draft strain on the standard exerted rearward of the beam. It will be noted that the upper edge of the standard section 4 will bear solidly against the top wall of the slot 3 above the bolt 8, thus taking the up thrust of the standard off of the bolt 8. The rear curved wall 13 of the slot is designed to afford a greater bearing surface for the standard when adjusted to the position shown in Fig. 2, so as

to brace the standard not only against up thrust but also against rearward thrust when its vertical lug 6 bears only at its extreme upper end against the wall 9. The 5 manner in which the standard fits into the slot 3 causes the side walls of the slot to brace the standard against lateral thrust.

Having thus described my invention, what I claim as new and desire to secure by Letters Patent, is:—

10 1. In a plow, the combination with a beam, of a standard adjustably connected to the beam and formed by a bent metal bar of single thickness, said bar having an upper portion of substantial length and said beam having a longitudinal bottom slot which snugly receives said upper portion of the standard and braces it against lateral strain, means to pivotally connect said standard to the beam, and abutting portions on the beam and standard which are adapted to sustain the thrust strains of the standard.

25 2. A plow comprising a beam having in its underface a longitudinally disposed slot which is shallow except at its forward end where its depth is increased by a vertical extension of the slot, a standard seated in said slot and pivoted near the rear end thereof to the beam, a vertical extension on the forward end of the standard which is adapted to project into said vertical extension of the slot, the rear edge of said vertical extension on the standard being struck on an arc from the pivot of the standard as a center, and means to fasten the forward end of the standard in adjusted positions in the slot, said means being adapted to permit the rear edge of said standard extension to bear against the rear wall of the vertical extension of the slot.

30 3. A plow comprising a beam having in its underface a longitudinally disposed slot which is shallow except at its forward end

where its depth is increased by a vertical extension of the slot, a standard seated in said slot and pivoted near the rear end thereof to the beam, a vertical extension on the forward end of the standard which is adapted to project into said vertical extension of the slot, the rear wall of the slot and the rear 45 edge of said vertical extension on the standard being struck on arcs from the pivot of the standard as a center, means to fasten the forward end of the standard in adjusted positions in the slot, said pivot and fastening 50 means being adapted to permit the standard at its forward end to bear against the rear wall of the vertical extension of the slot and at its rear end to bear against the upper wall 55 of the slot.

60 4. In combination, a plow beam having a narrow slot disposed centrally and longitudinally in its under face and having a vertical extension at its forward end, a plow standard having rigid therewith a top bar 65 which fits snugly into said slot and is laterally braced thereby, a vertical perforated lug at the forward end of said bar which fits into said slot extension, a pivot bolt which passes through the rear end of said top bar 70 to secure it and the standard to said beam, said standard having its upper end above said bolt curved relatively to said bolt as a center to maintain in its various adjusted positions a bearing against the top wall of 75 the slot which is correspondingly curved for that purpose, and a cross bolt that passes through one of the perforations in said lug to adjust the standard about its pivot while permitting the lug to bear against the rear 80 wall of said slot extension.

In testimony whereof I affix my signature.

WILLIAM A. KIMBELL.
